(57) **CLAIM**

The ornamental design for a shrink wrapped carton for electronic component, as shown.

DESCRIPTION

FIG. 1 is a perspective view of a shrink-wrapped package for an electronic component showing my new design.

FIG. 2 is a front view of the package shown in FIG. 1.

FIG. 3 is a rear view of the package shown in FIG. 1.

FIG. 4 is a left side view of the package shown in FIG. 1.

FIG. 5 is a right side view of the package shown in FIG. 1.

FIG. 6 is a top view of the package shown in FIG. 1; and,

FIG. 7 is a bottom view of the package shown in FIG. 1.

1 Claim, 6 Drawing Sheets
